UNITED STATES PATENT OFFICE.

ALBERT W. JOHNSON, OF NEW HAVEN, AND JOSEPH P. LAVIGNE, OF WALLINGFORD, CONNECTICUT.

EMBROIDERY ATTACHMENT FOR SEWING-MACHINES.

SPECIFICATION forming part of Letters Patent No. 329,564, dated November 3, 1885.

Application filed November 5, 1884. Serial No. 147,201. (No model.)

To all whom it may concern:

Be it known that we, ALBERT W. JOHNSON, a citizen of the United States, and JOSEPH P. LAVIGNE, a subject of the Queen of Great Britain, residing, respectively, at New Haven and at Wallingford, both in the county of New Haven and State of Connecticut, have invented certain new and useful Improvements in Embroidery Attachments for Sewing-Machines, of which the following is a specification, reference being had therein to the accompanying drawings.

Our invention relates to improvements in that class of embroidery attachments that have arms crossing the line of stitching or path of the needle of the machine at each ascent of the needle alternately in opposite directions, for delivering the embroidery-threads upon the surface of the fabric to be ornamented; and its objects are to produce a simple device for effecting a positive movement to these thread-delivering arms, and a single tension device for giving substantially a uniform tension at the same time to two embroidery-threads, whether of the same or of different sizes.

In the drawings, Figure 1 is a top view of the attachment complete, showing the course of the embroidery-threads from the spools to the ends of the thread-delivering arms. Fig. 2 is a side elevation of the attachment. Figs. 3 and 4 are an inclined section of a part of the attachment on the broken line $\alpha\alpha$, Fig. 2, showing the same parts in different positions. Fig. 5 is a vertical section of a part on the broken line $v\bar{v}$, Fig. 1, and Fig. 6 is a perspective of a portion of the spool-holder and tension-spring.

Similar letters refer to similar parts throughout the several views.

The frame A is provided with a shank, G, by which it may be attached to a presser-bar, Z, of a sewing-machine, and its front end is formed into a presser-foot, A', from which it inclines upward to its rear end. From one side of the frame a wing, H, is turned upward, and forms a support to which the bell-crank B is pivoted. At the end of the long arm of the bell-crank B is a fork, b, formed to engage with the needle-bar of a sewing-machine. To the short arm of the bell-crank B is hung a pawl, C, the

free end of which is pressed downward by a spring, c, secured to the bell-crank and made to engage with ratchet-teeth projecting upward around the edge of the upper surface of the cam-disk E, which is arranged to rotate in a plane parallel with the plane of the frame A. In the under flat side of the cam-disk E is a quadratic cam-groove, e, the center of the space inclosed by this cam-groove coinciding with the center of the disk. Its four angles are equidistant from this center, as are also its four sides, which curve inwardly toward the center. Projecting upward into the cam-groove e are two cylindrical studs, k k, the lower ends of which are securely fixed to the arms L M, upon which the cam-disk E rests, and which are attached by pivots i i to and rest upon the frame A, the studs k k being fixed to these arms between their free ends and the pivots i i. The post D, which operates as a pivot for the cam-disk E to rotate upon, is firmly fixed at its lower end to the frame A. Above the cam-disk, around the post D, is a shoulder, between which and the disk a spring-washer, F, is compressed to produce a desired amount of friction upon the disk and arms L M, upon which the disk bears. The upper end of the post D, being provided with a suitable opening, d, forms a guide for the embroidery-threads. To the rear end of the frame A is attached the spool-holder O by means of the lips h h, Fig. 6, which are turned under and made to clasp around the edges of the wing a. At the rear end of the spool-holder O, one above and one below, and attached to it by a single pivot, are the spool-arms T T, for holding spools of embroidery-thread, extending in a horizontal plane in opposite directions at right angles to the holder. These arms are prevented from turning upon their pivot in the direction in which the embroidery-threads are drawn from the spools by the lips o o, turned one upward and one downward from the edge of the holder; but they may be swung around in the opposite direction until they rest parallel with the holder. Resting upon the spool-holder O is a flat tension-spring, P, having a rib, p, struck across its front end, where it is somewhat wider than the spool-holder, so that the rib

projects over at each side beyond the edge of the holder, the points of contact of the spring with the holder being its rear end and the convex surface of the rib *p*. An adjusting-screw, *S*, passes through the tension-spring *P* and into the spool-holder, for regulating the pressure of the spring. The guide-studs *r r*, projecting upward from the spool-holder *O*, one upon each side of the rib *p*, operate as guides to the embroidery-threads *t t*. One of these guide-studs passes through a hole in the tension-spring *P*, thereby preventing the spring from turning upon the adjusting-screw *S*.

The threading and operation of our embroidery attachment are as follows: The spools of embroidery-thread are placed upon the spool-arms *T T*, from which the threads are drawn under the rib *p* of the tension-spring and between the guide-studs *r r* from opposite sides, so that they will be separated by the studs both in front and in the rear of and made to cross each other directly under the central part of the rib *p*, between it and the spool-holder *O*, so that the tension-spring will press the two threads together, one upon the other, against the surface of the spool-holder, whereby a suitable tension pressure is given to both threads whether of equal or unequal sizes, the desired pressure upon the threads being obtained by turning the adjusting-screw *S*. From the tension device the threads pass through the opening *d* in the post *D*, where they separate, one passing through the guide-loop *m* on the arm *L* and down through the eye *n* at its extreme end, the other passing in like manner through the guide-loop *m* and eye *n* of the arm *M*. When the arms *L M* are separated to their full extent, as shown in Fig. 4, it will be observed that the studs *k k* occupy positions on a line crosswise of the attachment in two opposite angles of the cam-groove *e* in the cam-disk *E*. Now, at the first ascent of the needle-bar of the machine the end of the bell-crank *B* connected therewith is raised, whereby the short arm to which the pawl *C* is hung is carried forward, and the pawl engaging with one of the ratchet-teeth on the cam-disk *E* causes the disk to rotate one-eighth of a revolution, which brings the cam-groove *e* therein to the position shown in Fig. 3. The studs *k k*, running in the cam-groove, are drawn by its rotary movement in toward the center of the disk until they occupy positions in the centers of two opposite inwardly-curved sides of the cam-groove, whereby the arms *L M*, to which these studs are fixed, turning on their pivots *i i*, are drawn together at their free ends, so that they cross the line of stitching in opposite directions and overlap each other. As the needle-bar descends, the cam-disk *E* and arms *L M* remain stationary, while the pawl *C* is drawn backward to its first position. At the next ascent of the needle-bar the cam-disk is again caused to rotate, as before, one-eighth of a revolution,

bringing the cam-groove again into the position shown in Fig. 4, by which movement the studs *k k* are thrown outward into two opposite angles of the cam-groove, causing the arms *L M* to separate at their free ends, and, re-crossing the line of stitching, swing back to the position first above described.

A continuance of the operation would be a repetition of the above-described movements of the parts. At each descent of the needle-bar the cam-disk *E* and thread-carrying arms *L M* remain stationary; but at each ascent of the needle-bar the cam-disk is caused to rotate one-eighth of a revolution, and by the action of the quadratic cam-groove therein upon the studs *k k* the arms *L M* are caused to take alternately the positions shown in Figs. 3 and 4, vibrating from one to the other, their extreme free ends traversing in a path in front of the needle across the line of stitching alternately in opposite directions, whereby the embroidery-threads are crossed and delivered upon the surface of the fabric being ornamented at each upstroke of the needle, and each stitch made by the machine fastens the embroidery-threads at their point of crossing securely to the surface of said fabric.

We do not claim, broadly, a combination of vibrating thread-carrying arms with a rotating cam or cam and ratchet for operating said arms; nor do we claim, broadly, spool-carrying arms pivoted to a holder or frame, for we are aware that prior to our invention such combinations have been made; but

What we do claim as our invention, and desire to secure by Letters Patent, is—

1. In an embroidery attachment, the combination of the vibrating arms *L M*, the rotating cam-disk *E*, held in frictional contact with said arms by the spring-washer *F*, the pivot-post *D*, forming a guide for the embroidery-threads, the pawl *C*, and bell-crank *B*, when constructed and arranged substantially as described, and for the purpose set forth.

2. In an embroidery attachment, a cam-disk arranged to rotate in a plane parallel with the plane of the frame, having in its flat side a quadratic cam-groove, the angles of which are equidistant from the center of the disk, in combination with two arms for delivering the embroidery-threads, separately pivoted to the frame, arranged to vibrate between the frame and cam-disk, and held in frictional contact with both by a spring, the said arms being provided with cylindrical studs engaging with and arranged to run in said cam-groove, whereby a rotary movement of the cam-disk imparts a vibratory motion to the arms, substantially as described and set forth.

3. In an embroidery attachment, the combination of the spool-holder *O*, adjustable tension-spring *P*, secured thereto, provided with a cross-rib, *p*, constructed to bear upon and press the embroidery-threads against the surface of said spool-holder, and guide-studs *r r*, fixed to said spool-holder, one upon each side

of said rib, whereby the embroidery-threads are made to cross each other directly under the central part of said rib, between it and the surface of said spool-holder, substantially as 5 and for the purpose set forth.

4. The combination of the tension-spring *P*, provided with a cross-rib, *p*, guide-studs *r*, spool-holder *O*, with spool-arms *TT*, pivoted thereto, and lips *oo*, formed upon said spool- 10 holder, constructed to operate as stops to pre-

vent said spool-arms from turning on their pivot in the direction in which the embroidery-threads are drawn therefrom, substantially as described.

ALBERT W. JOHNSON.
JOSEPH P. LAVIGNE.
